Term of patent 14 years

(Cl. D26—14)

FIG. 3

FIG. 4

FIG. 5

Figure 1 is a top plan view of a corner speaker enclosure showing my new design.

Figure 2 is a front elevation thereof.

Figure 3 is a side elevation thereof, the opposite side having substantially the same appearance.

Figure 4 is a plan view similar to Figure 1 but with the top cover removed.

Figure 5 is a horizontal sectional view of the enclosure taken on line 5-5 of Figure 3. This view is rotated 90° from the position of Figure 3.

I claim:

The ornamental design for a corner speaker enclosure as shown and described.
